SOLDERING GUN HOLDER

Charles G. Balkan, Jefferson St., Pinehurst, Mass.

Filed Apr. 24, 1964, Ser. No. 79,675

Term of patent 7 years

(Cl. D54—13)

I claim:

The ornamental design for a soldering gun holder, as shown and described.
